UNITED STATES PATENT OFFICE.

ABRAHAM BARCHOFF, OF NEW YORK, N. Y.

DESIGN FOR A METAL BORDER STRIP FOR A TRAY OR SIMILAR ARTICLE.

Application filed March 5, 1923. Serial No. 5,362. Term of patent 3½ years.

To all whom it may concern:

Be it known that I, ABRAHAM BARCHOFF, a citizen of the United States, and a resident of the city of New York, borough of Manhattan, in the county and State of New York, have invented a new, original, and ornamental Design for a Metal Border Strip for a Tray or Similar Article, of which the following is a specification, reference being had to the accompanying drawing, forming a part thereof.

The figure is a plan view of a metal border strip for a tray or similar article, showing my new design.

I claim:

The ornamental design for a metal border strip for a tray or similar article, as shown.

ABRAHAM BARCHOFF.
